Primary Examiner — Khawaja Anwar*Assistant Examiner* — Julice Seung Eun Oum(74) *Attorney, Agent, or Firm* — Leason Ellis LLP(57) **CLAIM**

The ornamental design of a direct drive bicycle trainer, as shown and described.

DESCRIPTION

FIG. 1 is a first isometric view of a first embodiment of a direct drive bicycle trainer incorporating our new design, wherein the portions in phantom form no part of the claimed design;

FIG. 2 is a second isometric view thereof;

FIG. 3 is a first side elevation view thereof;

FIG. 4 is a second side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a first isometric view of a second embodiment of a direct drive bicycle trainer incorporating our new design, wherein the portions in phantom form no part of the claimed design;

FIG. 10 is a second isometric view thereof;

FIG. 11 is a first side elevation view thereof;

FIG. 12 is a second side elevation view thereof;

FIG. 13 is a front elevation view thereof;

FIG. 14 is a rear elevation view thereof;

FIG. 15 is a top plan view thereof; and,

FIG. 16 is a bottom plan view thereof.
